ROAD MACHINE

Daniel E. Dillow, Gruver, Tex.

Application December 27, 1932
Serial No. 649,073

2 Claims. (Cl. 37—175)

This invention relates to road machines, and particularly to road machines designed for use in scraping road surfaces, during the process of leveling or repairing the surface.

5 The primary object of the invention is to provide a road machine of this character, so constructed that the scraping blades thereof may be adjusted to operate at various angles with respect to the vertical, to the end that the scraping blades will become beveled or sharpened under use, whereupon the blades may be reversed so that the blades may have a cutting action as well as a scraping action.

Another object of the invention is to provide 15 a machine including adjustable blades, and means for adjusting the blades, the adjusting means acting to securely hold the blades in their positions of adjustment, against severe strains directed to the blades, when the blades contact with obstructions in the path of travel of the machine.

A still further object of the invention is to provide a machine wherein the pivoted scraping blades may be adjusted simultaneously, thereby permitting the adjusting of the blades to be 25 accomplished uniformly and expeditiously.

Still another object of the invention is to provide means for adjusting the initial positions of the blades, with respect to the surface over which the machine is to operate, thereby adapting the 30 machine for use in scraping crowned road surfaces.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, 35 49 without departing from the spirit of the invention.

Referring to the drawings:

Figure 1 is a plan view of a road machine constructed in accordance with the invention.

45 Figure 2 is a sectional view taken on line 2—2 of Figure 1.

Figure 3 is a sectional view taken on line 3—3 of Figure 1.

Referring to the drawings in detail, the machine, which is in the form of a drag, comprises a frame indicated generally by the reference character 5, which frame embodies spaced angle bars 6 and spaced angle bars 7, the angle bars 7 being bolted to the bars 6, by means of the bolts 8, and 55 transversely disposed, bracing the bars 6.

The angle bars 6 are provided with openings arranged in spaced relation with respect to each other, the openings of one bar 6 being disposed in alignment with similar openings in the remaining bars.

60 Bolts 9 extend through the openings in the bars 6, and also pass through openings in the arms 10, the openings in the arms 10 being arranged in vertical spaced relation with respect to each other.

The lower ends of the arms 10 are twisted, as clearly shown by the drawings, so that they lie flat against the side faces of the scraping blades 11 to which the arms are bolted, as by means of the bolts 12.

65 Due to the arrangement of the openings of the arms 10, it will be seen that the blades 11 are supported in position and extended transversely of the bars 6, so that the blades will act as scrapers, as the machine is moved over the road surface. 70 The upper or free ends of the arms 10 are pivotally connected with the connecting bars 13, by means of the bolts 14, so that the bars 13 may swing forwardly or rearwardly, to accomplish the adjustment of the scraping blades.

75 As clearly shown by the drawings, these bars 13 are arranged in pairs at each side of the frame 5, the bars of each pair being connected by means of a curved rod 15, to the end that all of the bars and scraping blades are moved simultaneously, 80 when the adjusting means, to be hereinafter more fully described, is operated.

85 The adjusting mechanism comprises a pair of arms 16 and 17 respectively, which arms have pivotal connection with the upper ends of certain 90 of the arms 10, the inner ends of the arms converging towards the coupling 18, where it has pivotal connection therewith, through the medium of the bolt 19. This coupling 18 is formed with a threaded bore into which the threaded inner 95 end of the adjusting rod 21 extends, the rod 21 being also supported in an opening formed in the arm 23, and held against longitudinal movement by means of the nuts 22, positioned on opposite sides of the arm 23. This construction also permits of adjustment of the operating means.

100 A hand wheel indicated at 24 is connected with the outer end of the rod 21 so that rotary movement may be imparted to the rod 21, moving the coupling 18 and arms connected therewith, forwardly or rearwardly, according to the direction of rotation of the wheel 24.

105 The reference character 25 designates a hitch which is carried by the frame and affords means whereby a suitable power device not shown, may 110

be hitched to the machine, for moving the machine over the road surface.

From the foregoing, it will be obvious that due to the construction shown and described, the 5 hand wheel may be operated, tilting the scraping blades in such a way that the front edges thereof will become worn or beveled, whereupon the blades may be readily removed and reversed, so that the sharp edges of the blades will be directed 10 forwardly, causing a cutting action as well as a scraping action.

It will further be seen that by operating the hand wheel and adjusting means, the scraping blades will be tilted simultaneously and uniformly, 15 eliminating the necessity of adjusting one blade, and adjusting other blades with relation thereto, as is common in road machines of this type.

It might be further stated that due to the construction, the ends of the blades may be adjusted 20 vertically, thereby adapting the machine for use in scraping crowned road surfaces.

Having thus described the invention, what is claimed is:

25 1. In a road scraping machine, a frame includ-

ing spaced bars, transversely disposed bars secured to the first mentioned bars, arms having a plurality of openings formed therein, scraping blades connected with the arms, bolts extending through the first mentioned bars of the frame and the arms, adjustably connecting the arms to the frame, and means for operating the arms simultaneously to adjust the scraping blades.

80

2. In a road scraping machine, a frame including spaced bars, transversely disposed bars secured to the first mentioned bars, arms pivotally mounted on the frame, the upper ends of the arms extending above the frame, the lower ends of the arms extending below the frame, blades secured to the lower ends of the arms and arranged transversely of the frame, said arms having a plurality of openings formed therein and arranged in spaced relation with respect to each other, bolts passing through certain of the openings and through the frame, pivotally securing the arms to the frame, bars connected with the arms, and means cooperating with the bars for operating the arms and blades.
